CLAIM

We claim the ornamental design for a grip for a pan, as shown and described.

DESCRIPTION

FIG. 1 is a top perspective view of a grip for pan showing our new design;

FIG. 2 is a top plan view thereof;

FIG. 3 is a right-side elevational view thereof, the left-side elevational view being a mirror image of the right-side elevational view shown;

FIG. 4 is a front elevational view thereof, shown with the pan portion removed for ease of illustration;

FIG. 5 is a front elevational view thereof, shown with the pan portion for completeness of illustration;

FIG. 6 is a rear elevational view thereof; and,

FIG. 7 is a bottom plan view thereof.

The broken lines in the drawings are for illustrative purposes only and form no part of the claimed design.
